GLASS BLOCK ASSEMBLY FOR
NON-VERTICAL USECROSS-REFERENCE TO RELATED
APPLICATIONS

This application is a continuation of patent application Ser. No. 11/872,766, filed Oct. 16, 2007 now U.S. Pat. No. 7,526,901, which was a divisional application of patent application Ser. No. 10/705,702, now U.S. Pat. No. 7,373,763, filed Nov. 10, 2003, entitled Glass Block Assembly, which also claims the benefit of U.S. Provisional Patent Application Ser. No. 60/454,472, filed Mar. 13, 2003, entitled Structural Wall, Skylight and Flooring System For Use With Glass Blocks.

BACKGROUND OF THE INVENTION

1. Field of the Invention

The present invention is directed to glass block walls, skylights, and floors, and, more particularly, to an assembly of glass blocks held in a structural frame.

2. Description of Related Art

For many years, glass blocks have been used as building materials for walls, skylights, and floors.

There have been problems with existing systems for glass blocks. For one, the glass blocks are typically set in rigid or semi-rigid mortar which tends to crack and leak with age. When mortar is mixed at the job site, there is little control over the amount of water added and, therefore, the strength and weatherability of the mortar. Mortared block walls, even when reinforced, have limited structural strength. Alignment of blocks laid at the job site is often inconsistent. Finally, field weather conditions are often unpredictable, affecting the quality of mortared glass block walls built on site.

Glass block assemblies involving a framework for holding the glass blocks have been proposed, for example, in U.S. Pat. Nos. 4,058,943; 5,031,372; 5,042,210; and 5,218,806.

SUMMARY OF THE INVENTION

It is an advantage of the present invention to provide an improved glass block assembly which offers great structural strength and security independent of the blocks and sealants.

It is a further advantage to provide a glass block assembly in a frame that enables accurate alignment.

It is a still further advantage to provide a glass block assembly which seals the intersections between the blocks against water and air infiltration and a construction that directs water leakage, if any, to the exterior.

It is yet another advantage to provide a glass block assembly which allows replacement of blocks in a manner in which the new blocks and joints will have the same appearance as the original blocks and joints.

Briefly, according to this invention, there is provided an assembly of glass blocks held in a structural perimeter frame comprising a plurality of glass blocks each having two rectangular display faces and four edge faces, a rectangular structural perimeter frame having four sides, a plurality of primary muntins, and, when needed, a plurality of secondary muntins. Preferably, the muntins and structural perimeter frame are aluminum extrusions or steel fabrications. Each of the primary muntins comprises an elongate web with elongate stand-offs extending outward from the faces of the web and at least one elongate hollow boss integral with the web. The primary muntins extend entirely across the structural perimeter frame either vertically or horizontally. Each secondary muntin comprises an elongate web with stand-offs extending

2

from the faces of the web and at least one hollow boss integral with the web. The secondary muntins extend for a length that is just somewhat longer than a length of an edge face or a display face of the glass blocks. The widths of the primary and secondary muntins may be substantially the same or may differ. While primary muntins must always be used, the use of secondary muntins is optional.

A plurality of structural rods (e.g., steel rods) is inserted through the hollow bosses of the secondary muntins and 10 extends entirely across the structural perimeter frame. The rods also pass through holes in the primary muntins. Thus, the primary and secondary muntins form a matrix within the structural perimeter frame with openings for receiving the plurality of glass blocks.

15 The muntin matrix may be secured to the structural perimeter frame by nuts on threaded ends of the rods inserted through the hollow bosses of the secondary muntins and/or by rods inserted through the hollow bosses of the primary muntins or, alternatively, by other fasteners, such as screws, engaging the hollow bosses of the primary muntins.

The primary and secondary muntins are different in several ways. One difference is that a hollow boss in the primary muntin is not located at the same position across the width of the muntin as a hollow boss in the secondary muntin is located, thus enabling the rods to cross through the assembly without interfering with each other. The width of the muntins is substantially less than, equal to, or greater than the width of the edge faces of the glass blocks. A gasket, such as a rubber or plastic boot, flexible foam tape, or other suitable elastomeric material, is located on each edge face of the glass blocks (i.e., completely or partially surrounding a perimeter of each block) to form a compressible elastomeric spacer. The elastomeric spacers on the glass blocks contact the muntins when the glass blocks are engagingly inserted in the matrix. 30 Alternatively, the elastomeric spacers may be applied to the muntins, in which case the glass blocks engage the elastomeric spacers when the glass blocks are engagingly inserted in the matrix.

35 The glass blocks are sealed in the muntin matrix with 40 caulking material between the edge faces. The elastomeric spacers also serve as a proper breathable backer for the caulking, which will seal the joints between the glass blocks. One type of glass blocks typically has central recesses on the edge faces generally parallel to the exposed display faces. Preferably, the caulking enters the recesses. According to a preferred embodiment, the primary and secondary muntin webs have at least one edge having a bead thereon, and the assembly further comprises a plurality of elastomeric joint covers that snap over the beads. Preferably, the elastomeric joint covers have a graffiti-resistant coating.

45 According to one embodiment, at least one side of the structural perimeter frame comprises two channels: one channel with extending substantially parallel webs slides within the extending parallel webs of the other channel with a seal 50 therebetween permitting slight relative movement between the channels. Each channel has a center web with a non-metallic thermal break therein.

Briefly, according to this invention, there also is provided 55 an assembly of glass blocks held in a structural perimeter frame for non-vertical use similar to the assembly already described. In this assembly, each primary muntin is comprised of an elongate web with elongate stand-offs extending outward from faces of the web and at least one elongate hollow boss integral with the web. Stop flanges, perpendicular to the web, are integral with the primary muntins and arranged with gaskets for abutting edges of exposed glass block display faces.

Each secondary munin is comprised of a web with stand-offs extending from the faces of the web and at least one hollow boss integral with the web. Stop flanges, perpendicular to the web, are integral with each secondary munin and arranged with gaskets for abutting the edges of exposed glass block display faces.

A plurality of structural rods inserted through the hollow bosses of the secondary munins and passing through holes in the primary munins extends from side to side (i.e., across) the structural perimeter frame, such that the primary and secondary munins form a matrix within the structural perimeter frame with openings for receiving the plurality of glass blocks. Preferably, a plurality of structural rods is also inserted through the hollow bosses of the primary munins and extends from top-to-bottom (i.e., perpendicular to the rods inserted through the secondary munins) of the structural perimeter frame.

Preferably, the primary and secondary munins are configured such that the stop flanges of the secondary munins extend over the stop flanges of the primary munins. Gaskets abutting the stop flanges provide surfaces for receiving and supporting the edges of one display face of each glass block. The gaskets on the stop flanges of the primary munins are thicker than the gaskets on the stop flanges of the secondary munins, so that the glass blocks are equally supported by both primary and secondary munins' gaskets.

BRIEF DESCRIPTION OF THE DRAWINGS

Further features and other objects and advantages will become clear from the following detailed description made with reference to the drawings in which:

FIG. 1 is an elevation view of a portion of glass block assembly according to this invention;

FIG. 2a is an exploded isometric view of a munin grid and structural perimeter frame members for the glass block assembly of FIG. 1;

FIG. 2b is an assembled isometric view of the munin grid and structural perimeter frame;

FIG. 2c is an isometric view of a glass block with elastomeric spacers shown on the visible edge faces;

FIG. 2d is an isometric view of a portion of the glass block assembly according to this invention;

FIG. 2e is a partial view of a primary munin illustrating the use of a screw or a threaded rod to secure the munin to the structural perimeter frame;

FIG. 2f is a partial view of a secondary munin illustrating the use of threaded rods to secure the munin to the structural perimeter frame;

FIG. 3a is a broken away view illustrating the details of the joint between two glass blocks provided by a secondary munin, the details of a flexible structural perimeter frame, and the details of a two-part extruded edge spacer and illustrating how the munin matrix may be secured to the structural perimeter frame via screws threaded into the bosses of the primary munins;

FIG. 3b is a broken away view illustrating the details of a structural perimeter frame in the form of a channel and the two-part extruded edge spacer;

FIG. 3c is a broken away view of the details of a joint between two glass blocks according to an alternate embodiment of this invention;

FIG. 3d is a broken away view of the details of a joint between two glass blocks according to another alternate embodiment of this invention;

FIG. 3e is a broken away view of the details of a joint between two glass blocks according to another alternate embodiment of this invention;

FIG. 4 is similar to FIG. 3a further illustrating how the flexible structural perimeter frame can be secured to an adjacent wall, but FIG. 4 illustrates the joint between glass blocks provided by a primary munin and an attachment of the munin matrix to the structural perimeter frame via rods with nuts;

FIG. 5 is a broken away view that illustrates a transition between a glass block assembly and an insulated vision glass window;

FIG. 6 is a broken away view through a primary munin having perpendicular stop flanges for supporting a non-vertical glass block assembly;

FIG. 7 is a broken away view through a secondary munin having perpendicular stop flanges for supporting a non-vertical glass block assembly;

FIG. 8 is a partially exploded isometric view of the munin grid for supporting a non-vertical glass block assembly according to this invention;

FIG. 9 is a broken away view of a snap-on joint cover; and

FIG. 10 is an assembled isometric view of a munin form and structural perimeter frame of a glass block assembly according to this invention.

DESCRIPTION OF THE PREFERRED EMBODIMENTS

FIG. 1 shows a glass block assembly having an aluminum or steel structural perimeter frame supporting an extruded aluminum munin grid or matrix for positioning glass blocks. The grid or matrix is comprised of horizontal munins 3 and vertical munins 2. The structural perimeter frame is comprised of vertical and horizontal channel members 4, 5 held together by screw fasteners 9. The vertical (i.e., main or continuous) munins in this embodiment are referred to as primary munins or primary grid members as they extend uninterrupted from one side of the structural perimeter frame to the other. The primary munins are secured to the structural perimeter frame by fasteners such as screws 6. Alternatively, they may be secured by threaded rods 13 inserted through the primary grid members and secured by nuts 14 at each end thereof.

The rods extend entirely across the assembly and through the structural perimeter frame. In this embodiment, the horizontal (i.e., non-continuous) munins 3 are referred to as secondary munins or secondary grid members as they comprise many short sections that fit abuttingly between each primary munin 2. The secondary munins are secured in place by threaded rods 7 passing through each section of the secondary munins (in hollow bosses to be described) and through holes in the primary munins. The rods are secured by nuts 8 on each end thereof. The rods extend entirely across the assembly and through the structural perimeter frame so that the threaded ends are exposed for receipt of the nuts.

In the exploded isometric view of FIG. 2a and the assembled isometric view of FIG. 2b, the manner in which the primary and secondary munins are held in the structural perimeter frame by threaded rods and screw fasteners is readily apparent. As can be seen, the structural perimeter frame comprises channel members 4, 5 and extruded edge spacers 10. The details of the configuration of the primary and secondary munins, channel members, and edge spacers will be explained.

FIG. 2c is an isometric view of a glass block. The glass block has two display faces 15 and four edge faces 16. The edge faces may have central troughs. FIG. 2c also shows a

resilient elastomeric spacer 17 along the edge faces 16 of the block in preparation for sliding the block into the matrix.

The cross sections of the primary and secondary muntings are easily observed in FIGS. 2e and 2f. The muntings being extruded structures, all surfaces are parallel to the direction of extrusion and there are no totally enclosed volumes in the muntings. The primary muntings, as shown in FIG. 2e, have a web 20 that has offsets (raised flat portions or stand-offs) 21 and 22. The surfaces of the offset portions lie within two parallel planes that are spaced apart from each other. The distance between these planes partially determines the spacing between glass blocks in the glass block assembly. The primary munting has two hollow bosses 23, 24. The hollow bosses have axial gaps in their cylindrical walls opening to opposite sides of the munting. The outer diameters of the hollow bosses fall within the spaced parallel planes referred to above. The two hollow bosses 23, 24 are adjacent to each other and near the center of the width of the extruded primary munting.

The secondary muntings have a web 26 with offsets (raised flat portions or stand-offs) 27, 28 and spaced hollow bosses 29, 30. The surfaces of the offset portions 27, 28 lie within two parallel planes. The hollow bosses 29, 30 are positioned within the two planes.

Extending laterally from the primary and secondary muntings are webs 31, 32 that terminate in beads 33, 34, respectively. Snap-on joint covers 37 may be placed over the beads.

The width of the primary and secondary muntings may be the same or may differ.

The function of the offsets or raised flat portions 21, 22, 27, 28 on the muntings is to allow the glass block 1 when wrapped with the elastomeric spacer 17 to slide into position without allowing the elastomeric spacer to fall into a cavity and thus impede the smooth insertion of the block and elastomeric spacer assembly.

FIG. 2e shows how the primary munting may be fastened in position with screws 6 of sufficient diameter to thread into the inside of the hollow bosses or by steel rods 13 with diameters small enough to pass through the hollow bosses. For example, the inside diameter of the hollow boss 24 may be just large enough (for example, 0.211 inch diameter) to have a sliding fit with a steel rod $\frac{3}{16}$ inch in diameter. In that case, a $\frac{1}{4}$ inch diameter screw 6 will, alternatively, thread into the hollow boss 23. Similarly, FIG. 2f shows how the secondary munting is secured. The locations of the hollow bosses of the secondary muntings are different, however. The hollow bosses 29, 30 are spaced farther apart and closer to the edges of the munting. In this way, two steel rods can pass through a primary munting and two steel rods can pass through an aligned secondary munting without interfering. The primary muntings are provided with holes for the steel rods, which are held in the hollow bosses of the secondary muntings, to pass through.

Referring to FIGS. 3a, 3c, and 3d, there are shown sections through the joints between glass blocks, which joints are supported by secondary muntings 3. The elastomeric spacer 17 on the edge face of one glass block rests on the flat portions 27 on one side of the munting 3 and the elastomeric spacer 17 on the edge face of the adjacent glass block rests on the flat portions 28 on the other side of the munting. Preferably, the elastomeric spacer is made of an intumescent material to act as a fire barrier. The glass blocks are secured in place by a sealant 36 that is backed up by the elastomeric spacer 17. In the examples shown in FIGS. 3c and 3d, the sealant 36 covers the extruded munting or mostly covers the munting. The caulking material is typically a silicone resin or other elastomeric sealant. In the example of FIG. 3a, the bead 34 on the edge of

the munting is exposed sufficiently for the snap-on joint cover 37 to be affixed. Alternatively, as shown in FIGS. 3d and 3e, the bead 34 may be exposed or an extension 34a may be exposed. This alternative exposure may occur on primary and/or secondary muntings.

Referring to FIG. 3a, there is shown an extruded aluminum edge spacer 10 which is placed within the structural perimeter frame and is adjacent to the glass block 1 at the perimeter of the glass block assembly. The edge spacer 10 is captured against a channel 5a when screws 6 are driven into the primary munting (not shown). The edge spacer comprises a web that, as shown, has two spaced halves 10a and 10b. The web has flat portions 11 and flanges extending from the sides with a beaded edge (similar to the bead 33, 34 of muntings 2, 3). The flat portions 11 have the purpose of abutting the elastomeric spacer 17 on the perimeter face of a glass block. The edge spacer has bores, one on each side, for receiving threaded rods (not shown) or screws 6. In FIG. 3a, screws extend through the bores in edge spacer 10 and enter the hollow bosses of a vertical primary munting (not shown). In FIG. 3b, threaded rods extend through channel 38, bores in the edge spacer 10, and continue through a primary munting (not shown).

Referring again to FIG. 3a, an edge spacer 10 is secured to an adjustable frame which comprises two two-part facing perimeter channels 5a, 5b with substantially parallel side flanges and with channel 5b abutting substrate 40. The side flanges of channel 5a slide within the side flanges of channel 5b. A gasket 41 is positioned between the side flanges that slide relative to each other. The two parts of each of the channels 5a, 5b are separated by a thermal break which may comprise a rigid plastic filler 42, such as urethane, that is captured by each part of the channels. The channels are preferably extruded aluminum and the plastic fillers are rigid materials, such as urethane. Channel 5a has bores, one in each part, for receiving threaded rods or screws. In FIG. 3a, screws extend through the bores in channel 5a and enter the hollow bosses of a perpendicular perimeter channel (not shown). FIG. 4 (at the left side) shows an edge spacer 10 and an adjustable frame comprising two facing perimeter channels 4a, 4b similar to that shown in FIG. 3a. Screws 43 through one channel 4b fasten it to a wall or other substrate 39, and threaded rods 7 and nuts 8 in the other channel fix a secondary munting in place.

FIG. 5 illustrates an intersection between two perimeter channels 4a, 4b in an adjustable gasketed manner. It also illustrates a transition from the glass block system herein to a panel with similar perimeter structural framing and which uses vision glass 44 by a vision glass fixing method well known in the industry.

FIGS. 6, 7, and 8 relate to an embodiment of this invention for horizontal placement of the glass blocks as in skylights or load-bearing floors. The extruded primary munting 45 shown in section in FIG. 6 has not only the web 20, offsets 21, 22 and hollow bosses 23, 24 as already described with reference to vertically oriented embodiments, but has a perpendicular flange 47 at the base and extending to an opposite side thereof. Positioned on the flange on each side is a gasket 48 upon which edges of the display face of the glass block 1 rest. Primary munting 45 further includes a primary top edge 20a opposite the flange 47.

FIG. 7 shows a section through the secondary munting 46 which also has a perpendicular flange 49 with a gasket 50 positioned thereon for supporting edges of the display faces of the glass blocks. Each secondary munting has a secondary to edge 29a at the to hereof defined by hollow boss 29. In order to enable the perpendicular flange 49 on the secondary munting to be spaced above and rest on the perpendicular flange 47

of the primary muntin as shown in FIG. 8, the primary muntin must extend downwardly beyond the secondary muntin. However all of the support gaskets for a given glass block must be on the same level. To this end, the gasket 48 positioned on the perpendicular flange 47 of the primary muntin is sufficiently deep such that its total height equals the height of the flange 49 plus gasket 50 of the secondary muntin. The secondary flanged muntin is typically oriented perpendicular to the primary flanged muntin such that when flanges 49 rest on top of flanges 47 and are placed in between sections of gasket 48, the complete perimeter of the glass blocks is supported. The tops of the gaskets 48 and 50 form a continuous square frame and are on the same plane.

Should leakage water enter the system, it will run into a cavity 51 in flanged muntin 46 and then, owing to the overlapping flanges, the water will be directed into a cavity 52 in flanged muntin 45 where it can flow to the perimeter of the system and be exhausted.

The elastomeric spacer and the edge faces of the glass blocks are not shown in FIGS. 6, 7, and 8. A backing pad 54 is shown in FIGS. 6 and 7 covered by sealant 36. As shown, backing pad 54 is disposed on the secondary top edge 29a of secondary muntin 46 adapted to cover the hollow boss 29. FIG. 8 is an isometric view that illustrates the positioning of the secondary muntins 46 and the intersection with the continuous primary muntins 45 so as to form a gridwork or matrix for a floor or skylight assembly of glass blocks. It also illustrates securing of the secondary muntins 46 with steel rods 7 (passing through them) and the securing of the primary muntins 45 with steel rods 13 (passing through them) or, alternatively, by screws 6 which thread into the hollow bosses at the ends of the primary muntins. In addition, FIG. 8 shows how the flanges 49 of the secondary muntins rest on the flanges 47 of the primary muntins. Holes 57 and notches 56 are made in the primary muntins 45 to accept the steel rods 7 which provide strength and alignment. For instance, primary muntin 45 has one or more notches 56 defined along its primary top edge 20a, and each hollow boss 29 making up secondary top edge 29a aligns with each notch to further accept the same steel rods 7.

FIG. 9 is a section through the elastomeric joint cover 37 previously described. It is of an elastomeric material, such as Santoprene, comprising a hard durometer material at its core and a soft durometer material in the area marked 60. The joint cover has two barbed extensions 59 which can be snapped over the beads on the edges of the primary and secondary muntins. The surface of the joint cover is preferably provided with a graffiti-resistant coating 61.

FIG. 10 shows an alternative embodiment of a glass block assembly having a structural perimeter frame, for example, of aluminum or steel, supporting a muntin array for positioning

glass blocks. Preferably the muntins are extruded aluminum. As shown, the array is comprised of primary muntins, no secondary muntins are used. The primary muntins 2 and the structural perimeter frame are constructed similarly to the above described embodiment of FIG. 1 and, therefore, are not further described here. During installation of the glass block assembly, the glass blocks are received in abutting relationship to each other (preferably with plastic spacers separating the adjacent blocks) within the parallel primary muntins 2.

Having thus defined our invention in the detail and particularity required by the Patent Laws, what is desired to be protected by Letters Patents is set forth in the following claim.

We claim:

1. An assembly of glass blocks held in a structural frame for non-vertical use comprising:
a plurality of glass blocks having two rectangular display faces and four edge faces;
a rectangular structural frame having four sides;
a plurality of extruded primary muntins, each said primary muntin having a primary top edge and one or more notches defined along said primary top edge to accept steel rods;
a flange opposite said top edge, said flange integral with each primary muntin and perpendicular thereto;
a gasket on said flange of said primary muntin abutting the edges of an exposed glass block display face;
a plurality of extruded secondary muntins, each said secondary muntin having a hollow boss at the top thereof defining a secondary top edge, each said hollow boss aligned with each said notch of said primary muntin to accept said steel rods;
a backing pad disposed on said secondary top edge and covering said hollow boss;
a stop flange opposite said secondary top edge, said stop flange integral with each secondary muntin and perpendicular thereto, said stop flange sized to fit into a section of said gasket of said primary muntin, wherein upon assembly the total height of the flange and gasket equals the height of the stop flange to equally support said glass blocks.

2. The assembly of claim 1, wherein each said secondary muntin further includes a gasket on said stop flange.

3. The assembly of claim 2, wherein the gasket on said primary muntin is thicker than the gasket on the secondary muntin such that upon assembly all of said gaskets are on the same plane to form a continuous frame.

4. The assembly of claim 1, further comprising holes defined in said primary muntin adapted to accept said steel rods for strengthening and aligning said assembly.
